SHARPENING DEVICE

Benjamin H. Johnston, Oklahoma City, Okla.

Application March 4, 1946, Serial No. 651,762

6 Claims. (Cl. 51—59)

1

This invention relates to a device for sharpening razor blades, and more particularly to a device for straightening and drying the edge of a blade adapted to be used in a safety razor.

After a razor blade has been used, portions of the edge thereof will tend to become out of alignment and while not dull, prevent smooth cutting by the blade when in use. These misaligned portions will tend to collect water and unless the blade is dried after use, the edge of the blade will rust and thus tend to cause the blade to lose its usefulness. With the devices now in use requiring a honing action, the blade is worn away by abrasion and the blade soon becomes useless. The misaligned places are very minute and it requires a device of fine precision to realign the cutting edge of the blade to restore the same to its original shape.

The principal objects of the present invention are to provide a device for sharpening safety razor blades by a simultaneous pressing action on both sides of the blade between two smooth surfaces and withdrawing the blade to straighten the edge of the blade; to provide a device for drying the edge of the blade at the time of straightening the same; to provide a device of this character which contacts the edge of the blade and has a lateral moving action instead of longitudinal as in former devices; and to provide a device of this character simple, economical to manufacture, and efficient in use.

In accomplishing these and other objects of the present invention, I have provided improved details of structure, the preferred form of which is illustrated in the accompanying drawings, wherein:

Fig. 1 is a perspective view of my invention showing a razor blade in position for sharpening.

Fig. 2 is a vertical cross section through the device showing the blade inserted therein ready for sharpening.

Fig. 3 is a transverse cross section through the device showing the smoothing jaws about to contact the cutting edge of the blade.

Fig. 4 is a transverse cross section through the device showing the smoothing jaws in contact with the blade.

Fig. 5 is a plan view particularly illustrating the smoothing jaws and the trunnions on the end thereof engaging the spreader.

Fig. 6 is a perspective view of the spreader particularly showing the cam surface for contacting the trunnions of the smoothing members.

Referring more in detail to the drawings:

1 designates a sharpening device embodying the features of my invention comprising a case or housing 2, a frame 3 slidable within the housing by a handle 4. The housing is substantially rectangular in shape, having sides 5 and 6 and ends 7 and 8 and having a closed bottom 9 pro-

2

vided with an opening 10 for the handle shaft 11 of the handle 4. The top of the housing is provided with a plate 12 secured to the ends of the housing by screws or the like 13. The plate is provided with a longitudinal slot 14 for a purpose later described. The ends of the housing are provided at substantially the centers thereof near the upper part with thickened walls 15 and 16 provided with openings 17 and 18 adapted to be closed by plates 19 and 20 by any suitable means, such as screws or the like, for a purpose later described. The housing may be made of any suitable material, such as wood, metal, plastic or the like.

The jaw carrying frame 3 operable within the housing comprises guides 22 and 23 having their ends adapted to slide within each end of the housing 2 as best illustrated in Fig. 2. The guides are provided with openings at substantially the centers thereof for receiving a shaft 24 which is rigidly secured in said openings. The inner sides of the case are provided with perpendicular slots 25 and 25' adapted to receive the ends of the guides to form a trackway for the guides in moving up and down in the case as later described. The trackways run parallel to each other and must be smooth to provide accuracy of operation.

Rigidly secured to substantially the center of the shaft 24 is a collar 26 having a boss 26' provided with an internally threaded bore 27 adapted to receive the threaded end 28 of the shaft 11 of the handle 4. The handle 4 may be swedged onto the shaft 24 or otherwise suitably secured thereto.

Located upon the shaft 24 are collars 30 and 31 and 32 and 33. The collars are loosely attached to the shaft and provided with arms 34 and 35 and 36 and 37 which extend upwardly toward the open end of the housing and are substantially V-shaped, the lower part of the V being slightly longer than the upper part. The upper ends of the arms carry elongated jaws 38 and 39 which extend lengthwise of the housing and parallel to each other to form mating faces for contacting the blade as later described. The outer ends of the jaws are provided with trunnions 40 and 41 also for a purpose later described.

The jaws 38 and 39 are preferably made of brass or steel and must be extremely accurate. The trunnions must be smoothly finished and hardened and the face of the jaws milled to a smooth surface and be a true cylindrical section coaxial with the trunnions on the ends thereof and parallel to the bearing axis. The jaws are preferably made from one piece of material and are substantially semi-circular in shape as best illustrated in Figs. 3 and 4. The jaws may be secured to the arms by any suitable method, but preferably the arms carry cylindrical bars 43 which engage in semi-circular grooves 44 of the

jaws, and the bars are secured therein by brazing or the like.

I preferably provide a facing 45 for the jaws 38 and 39 of leather, woven linen, cotton cloth, or other suitable material, which is secured thereto by glue or other suitable manner.

In order to provide inward tension on the arms and jaws respectively, I preferably provide a C-shaped spring 47, made preferably from spring steel and having ends fitting in longitudinal grooves 48 in the jaws 38 and 39 and secured thereto by brazing or the like. The spring is adapted to be located between the respective pairs of arms 34-35 and 36-37. The jaws 38 and 39 when assembled on the shaft 24 must meet exactly the whole length of their opposing faces on a line parallel to the axis of the shaft.

The openings 17 and 18 in the ends of the housing are substantially trapezoidal-shape and are provided at each end with slots 50 and 51 closed at the inner ends by lugs or stops 52 and 53 on the respective sides of the openings. Located within the openings 17 and 18 are spreader members 55 and 56. The spreaders are also of substantially trapezoidal-shape conforming to the shape of the openings 17 and 18 wherein the lower ends are narrower than the upper ends and the sides diverge upwardly. The spreaders are provided on their respective ends with lugs 57 and 58 adapted to operate in the slots 50 and 51 and engage against the lugs 52 and 53. The upper portions of the inner faces of the spreaders are undercut to provide downwardly and inwardly sloping cam surfaces 60 and 61 adapted to engage the trunnions and cooperate with the sides of the spreaders in controlling movement of the jaw members as will later be described. The outer faces of the spreaders are provided with recesses 62 and 63 adapted to receive coil springs 64 and 65 having one end engaging against the inner side of the plates 19 and 20 on the respective ends of the housing and the opposite ends against the spreaders to urge the spreaders inwardly against the lugs 52 and 53 of the housing.

I also preferably provide plates 19 and 20 to bridge the innerside openings 17 and 18 in the housing and against which the inner faces of the spreaders may seat when pressed inwardly by the springs 64 and 65. The plates are preferably made of sheet material and have flanges which are secured to the inside of the ends of the housing by screws or the like 73.

75 designates a blade clamp comprising two sheets of material 76 and 77 adapted to lie flat on the top plate 12 of the housing. The plates 76 and 77 are provided at their mating edges with lateral flanges 78-79 and 80-81 (Fig. 3) for providing clamping faces for the razor blade 82. Each face of the plates 76 and 77 is provided on its inner face substantially midway from one side thereof with a longitudinal lug or rib 83 offset from one another. The rib on each face is adapted to fit in a groove 84 in the face of the plate opposite said rib. When the blade 82 is placed between the clamping faces of the blade clamping plate the ribs will extend through the opening 85 in the blade to hold the blade rigidly in clamping position and the inner flanges 79 and 81 on the plates are inserted in the longitudinal slot 14 of the plate 12. Spring clips 86 are provided on the respective sides of the housing for clamping the blade plates in place when inserted for use.

Operation of a device constructed as described is as follows:

After the razor blade has been inserted in the blade clamp 75 as shown in Fig. 1, the operator grasps the housing 2 with one hand and the handle 4 with the other and by pressing upwardly on the handle and downwardly on the housing, the framework 3 including the arms and jaw members will be raised upwardly in the housing and the trunnions 40 and 41 on the respective ends of the jaw members being in contact with the diverging side faces of the spreaders will move the jaws apart until the trunnions reach and override the upper ends of said spreaders allowing the jaw members to move inwardly under pressure of the C-shaped spring 47 so the surfaces of the jaw members will contact the blade preferably about $\frac{1}{16}$ " from the cutting edge. Then downward pull on the handle member will cause the ends of the trunnions to move downwardly on the cam faces 60 and 61 forcing the spreaders outwardly in the openings 17 and 18 compressing the springs 64 and 65. Outward movement of the spreaders permits the trunnions to engage the inner faces 59 of the spreaders on further downward movement of the handle member until the trunnions reach a position adjacent the lower ends of the spreaders where the width of said spreaders permits same to move inwardly between said trunnions whereby said trunnions again engage the sides of the spreaders. The downward pull causes the surfaces of the jaw members to make a wiping action on the respective sides of the blade until the faces of the jaw members pass the edge of the blade, thereby smoothing and realigning the cutting edge of the blade and removing any moisture from the edge of the blade. When the spreaders have moved between the trunnions at the end of the downward movement of the handle, said handle is moved upwardly with the trunnions in contact with the diverging sides of said spreaders to again spread the jaws apart until the trunnions reach the upper ends of said spreaders. This action may be repeated several times so that the cutting edge of the blade will be entirely smoothed out and realigned for further use. When one edge of the blade has been sharpened the blade may be removed and reversed in the clamp to sharpen the other edge.

I preferably subject the razor blade to the smoothing and drying action of my device after each use as I find I receive better results than leaving the razor until just before use as is often the case.

While I have here described a device for conditioning two-edged blades, it will be obvious my device may be adapted for conditioning single edge blades.

It will be obvious from the foregoing that I have provided an improved device for sharpening safety razor blades whereby a pressure is applied on both sides of the cutting edge simultaneously, thereby straightening the edge of the blade and removing moisture therefrom and restoring the cutting edge of the blade to its original form.

What I claim and desire to secure by Letters Patent is:

1. A device for conditioning the cutting edge of a razor blade comprising, a housing having a closed bottom, side and end walls and an open top, said end walls being provided with an opening near the top of the housing, a frame reciprocable in said housing, means for clamping a blade in the open end of the housing, oppositely facing jaws pivotally carried by the frame, spreaders having tapered side edges carried by

the openings in the end walls, means for reciprocating said frame in said housing, means on said jaws engaging the tapered side edges of the spreaders to separate said jaws upon movement of the frame toward the blade, said spreaders having cam surfaces engaging the means on the spreaders to cause said jaws to contact said blade above the cutting edge at the limit of travel of the frame toward said blade, whereby reciprocation of the frame away from the blade will draw the jaws across the edge of the blade to condition the same.

2. A device for conditioning the cutting edge of a razor blade comprising, a housing having one end closed and provided with an opening adapted to receive a handle, said housing having longitudinal slots in its walls, guides adapted to reciprocate in said slots, a shaft having its ends secured to said guides, a collar carried by the shaft having a centrally bored hub adapted to receive said handle, arms pivotally secured to the shaft, oppositely facing jaws secured to the outer ends of said arms having honing surfaces, trunnions on said arms, a spring urging said jaws together, means for holding a blade in the open end of the housing, and spreaders carried by the housing and having cam surfaces engaging said trunnions to spread the jaws apart upon reciprocation of the frame by the handle in a direction toward the blade and to close said jaws for contacting the edge of the blade upon movement of the frame away from the blade, whereby the honing surfaces will be drawn across the edge of the blade to condition the same.

3. A device for conditioning the cutting edge of a razor blade comprising, a housing having one end closed and provided with an opening adapted to receive a handle, a frame reciprocable in said housing operable by the handle, said housing having longitudinal slots in its walls, said frame including guides adapted to reciprocate in said slots, a shaft having its ends secured to said guides, a collar carried by the shaft having a centrally bored hub adapted to receive said handle, arms pivotally secured to the shaft, oppositely facing jaws having honing surfaces secured to the outer ends of said arms, trunnions on said arms, a spring urging said jaws together, means for holding a blade in the open end of the housing, and spreaders carried by the housing and having cam portions engaging said trunnions to spread the jaws apart upon reciprocation of the frame toward the blade and having cam portions engaging the trunnions to move the jaws away from the blade, whereby the honing surfaces of the jaws will move across the edge of the blade by a wiping action to condition said edge upon reciprocation of said frame.

4. A device for conditioning the cutting edge of a razor blade comprising, a housing, means for holding the blade extended in the housing, stropping members, means for reciprocating the stropping members toward and away from the edge of the blade, trunnions on the stropping members, spreaders resiliently mounted in the housing, said spreaders having diverging faces adapted

to be contacted by the trunnions upon movement of the stropping members toward the cutting edge of the blade, and cam faces on the spreaders adapted to be engaged by the trunnions to move the spreaders out of the path of the trunnions during movement of the stropping members away from the blade, the reciprocating movement of the stropping members permitting the same to engage the cutting edge of said blade in a wiping action to condition said edge.

5. A device for conditioning the cutting edge of a razor blade comprising, a housing, means for holding the blade extended in the housing, stropping members, means for reciprocating the stropping members toward and away from the edge of the blade, trunnions on the stropping members, spreaders resiliently mounted in the housing, said spreaders having diverging faces adapted to be contacted by the trunnions upon movement of the stropping members toward the cutting edge of the blade, cam faces on the spreaders adapted to be engaged by the trunnions to move the spreaders out of the path of the trunnions during movement of the stropping members away from the blade, and means for holding the stropping members in engagement with the blade whereby said members will be drawn over the edge of the blade when the stropping members are moved away from the blade.
6. A device for conditioning the cutting edge of a razor blade comprising, a housing, means for holding the blade extended in the housing, stropping members, means for reciprocating the stropping members toward and away from the edge of the blade, a substantially C-shaped spring engaging the stropping members to urge said members together, trunnions on the stropping members, spreaders resiliently mounted in the housing, said spreaders having diverging faces adapted to be contacted by the trunnions upon movement of the stropping members toward the cutting edge of the blade, cam faces on the spreaders adapted to be engaged by the trunnions to move the spreaders out of the path of the trunnions during movement of the stropping members away from the blade, and means for holding the stropping members in engagement with the blade whereby said members will be drawn over the edge of the blade when the stropping members are moved away from the blade.
